(57) **CLAIM**

The ornamental design for an electrical connector, as shown and described.

DESCRIPTION

In a preferred embodiment, the electrical connector is a fitting of an electrical and electronic system of automobiles by means of cable harnesses, and the like.

FIG. 1 is a top perspective view of an electrical connector showing my new design;

FIG. 2 is a bottom perspective view thereof;

FIG. 3 is a right side elevational view of an electrical connector showing my new design;

FIG. 4 is a left side elevational view thereof;

FIG. 5 is a rear elevational view thereof;

FIG. 6 is a front elevational view thereof;

FIG. 7 is a bottom view thereof; and,

FIG. 8 is a top view thereof.
